UNITED STATES PATENT OFFICE.

JAMES C. GOODING, OF WELLSTON, OHIO.

BUILDING CONSTRUCTION.

Application filed December 26, 1922. Serial No. 608,984.

This invention relates to fire proof building walls and partitions, and more particularly to studs for supporting plaster boards or similar slabs in partitions or ceilings of buildings.

The object of the invention is to provide a metallic partition stud by the use of which a double-walled or hollow partition may be readily formed and a structure produced which is strong and durable.

Another object is to provide a studding of this character which can be combined in various ways to support a number of partitions or walls arranged in different ways as will be pointed out in the detail description appearing hereinafter.

Another object is to provide a stud of this character in which a solid core is encased in a metal shell and the members of the shell secured together by clamping clips.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a transverse section of one form of studding embodying this invention.

Fig. 2 is a similar view of another form thereof.

Fig. 3 is a perspective view of one form of connecting clip for uniting the parts of the shell of the studding.

Fig. 4 is a similar view showing another form of clip.

Fig. 5 is a transverse section showing the clip in position before the flanges thereof are clinched down.

Fig. 6 is a transverse section showing another form of studding.

Fig. 7 is a similar view of still another form.

Fig. 8 is a similar view of another form embodying this invention, and

Fig. 9 is a transverse section of still another form.

In the embodiment illustrated in Fig. 1, a straight stud is shown comprising a wooden core 1 rectangular in cross section and enclosed in a metal sheathing 2 composed of

two similar sections 3 and 4 shaped when united to completely encompass the core 1. Each of these sections is provided along its side edges with laterally and outwardly extending plates 5, having outturned flanges 6, the plates 5 of one section being designed to abut those of the other when the sections are assembled as shown clearly in Fig. 1, with the flanges 6 of the two sections extended laterally outward and in the same plane, 60

Securing clips 7 are designed for connecting the flanges 6 of the shell sections 2 and 3 and in the form shown in Fig. 1, these clips are constructed of flat strips of sheet metal, 70 each of said strips being bent longitudinally to form continuous flanges 8 and 9 connected by the integral web 10. This web 10 may have mortar clinching apertures 11 formed therein if desired, but these apertures may be omitted. The web 10 of these clips is of a width corresponding to the combined width of the flanges 6 of the two sections as is shown clearly in Fig. 5, and when applied, fits closely around the outer faces of 80 these flanges and the flanges 8 and 9 of the clips are clinched down around the flanges 6 into the full line position shown in Fig. 1, said position being shown in dotted lines in Fig. 5. 85

It will thus be seen that this arrangement of the plates 5 and flanges 6 with the securing clips fastening the sections together, substantially U-shaped seats 12 are formed to receive the plaster boards to be 90 supported therein.

In the form shown in Fig. 2, the stud is of a different configuration in transverse section, the core 1^a being substantially rectangular with riblike projections 13 and 14 95 on two sides thereof which extend longitudinally throughout the length of the core to assist in forming seats for the boards to be supported thereby.

As shown in this figure, the metal sheath- 100 ing 2^a is composed of three sections instead of two. The sections 15 and 16 are correspondingly shaped to fit the ribs or arms 13 and 14 of the core, and these sections are united along one side edge by a clip 7^a such as that shown in detail in Fig. 3. The web portion 10^a is substantially V-shaped in cross section to fit snugly between the parallel flanges 6^a carried by the plates 5^a which extend laterally at right angles from the sections 15 110 and 16, said flanges 6^a being arranged parallel with the side walls of the shell sections.

The correspondingly shaped sections 15 and 16 are connected by a section 17 which is right angular in cross section to fit the correspondingly shaped corner of the core 1^a.

6 This section 17 is provided along its side edges with inturned lips 18 which are designed to interlockingly engage the flanges 6^b at the outer edges of the sections 15 and 16.

10 In the form shown in Fig. 6, the core 1^b is L-shaped in cross section and the shell 2^b which encompasses it is correspondingly shaped, being composed of three sections 19, 20 and 21. The sections 19 and 20 are sub-

15 stantially U-shaped in cross section to fit the ends of the arms of core 1^b and are similar in form, and are provided with laterally extending flanges 22 having inturned lips 23 which are arranged parallel with the side walls of the section to form seats between them and said side walls for the boards to be supported.

20 The inner lips 23 of the sections 19 and 20 are connected by a connecting strip or clip 7^b similar to that shown in detail in Fig. 3, the flanges thereof being clamped around the flanges 23 and thus securely connecting the sections 19 and 20.

25 The member 21 is folded longitudinally to provide at the corner of core 1^b a longitudinally extending rib 24. The side walls of this member 21 which fit around the corner of the outer face of core 1^b have outwardly and obliquely disposed arms or plates 25 merging at their edges into flanges 26 which are disposed parallel with the lips of flanges 22 lying close against the outer face of said lips. These flanges 26 are provided with inturned lips 27 which clamp 30 around the edges of lips 23 and securely connect the member 21 with the members 19 and 20, thereby forming a shell 2^b completely encompassing the core 1^b.

35 The arrangement of the sheathing sections 19 and 20 of the shell above described, provides at the inner corner of elbow or core 1^b between it and the sheathing, an air space 28, while the oblique arrangement of the arms 25 of the section 21 provide air spaces 40 29.

45 In the form shown in Fig. 7, the studding is similar to that shown in Fig. 1, being illustrated in connection with an upright 31 having sockets 32, 33 and 34 to receive the 50 projecting portions of the member 30.

55 In the embodiment illustrated in Fig. 8, the core 35 is made cruciform in cross section and encased in a metal sheathing 36 composed of four sections 37, 38, 39 and 40, 60 which are all exactly alike, being similar in form to the sections 19 and 20 shown in Fig. 6, one being provided for the end of each of the arms of the core. These sections are connected in the angles between said arms by 65 attaching clips or strips 41 which are ex-

actly like those shown at 7^b in Fig. 6. This arrangement provides four air spaces 42 at the angles of the arms of the core between them and the shell sections.

70 In the form shown in Fig. 9, the invention is applied to a right angled stud which comprises a hard wood core 43 shown substantially T-shaped in cross section and encased in a metal sheathing 44 composed of four sections 45, 46, 47 and 48, the first three being constructed exactly alike and similar to those shown in Fig. 8 and which are connected by connecting strips or clips 49 similar to those shown in Fig. 8.

75 The section 48 which connects sections 45 and 47 is made in the form of a plate designed to rest against the outer face of the head of the core 43 and has outwardly and obliquely extending arms 50 from which extend flanges 51 within inturned lips 52. 80 The flanges 51 fit against the outer faces of the flanges of the sections 45 and 47 and the lips 52 around the edges of these flanges. This arrangement of the section 48 in connection with the sections 45 and 47 provide 85 air chambers 53.

85 Air seats 54 are also formed at the junction of the core 43 with its stem between said portions and the shell sections 45, 46 and 47.

90 In the form shown in Fig. 8, eight plate receiving seats are formed while in Fig. 9, six only are provided, thus adapting the studding to be used with doubled outer walls 1.

95 The connections of the various sheathing sections by the V-shaped or trough-shaped sockets strengthens and reinforces the sheathing at the outer edges of the seats formed thereby.

100 From the above description it will be obvious that with some slight variations, these metal encased studs and plates may be used to completely construct and fit walls, floors or ceilings and roof being formed therefrom. The wooden cores used permit fastening of 110 any wooden trimming or finishing to the walls without any special grounds, furring or blocking being employed.

115 The apertures 11 formed in the shell section connecting strips, provide mortar clinching holes which may be used at the option of the builder.

120 It is of course understood that the arrangement above described of the sheathing sections and cores is designed to form seats in which plaster or other wall boards may be mounted and these boards may vary in thickness for either the outside or inside, all having nonconducting air chambers which render the partitions or walls substantially sound proof.

125 I claim:—

1. A fire-proof construction including a solid wooden core, a sectional casing having lateral offset portions, adapted to encase the 130

core, and removable clips adapted to embrace the offset portions of the sections to hold the sections in position on the core.

2. A fire-proof construction including a solid wooden core, a sectional casing adapted to encase the core, said sections having adjacent offset portions, said offset portions embodying laterally extended flanges, clips adapted to be positioned on the laterally extended flanges, said clips having portions thereof engaging the inner surfaces of the laterally extended flanges to hold the sections together.

3. A fire-proof construction including a solid wooden core, a sectional casing constructed to conform to the shape of the core and adapted to encase the core, the sections embodying laterally extended portions terminating in right angled flanges, and means embracing portions of the right angled flanges to hold the sections of the casing connected.

In testimony that I claim the foregoing as my own, I have hereto affixed my signature.

JAMES C. GOODING.
